UNITED STATES PATENT OFFICE.

JOSEPH F. PARKS, OF WICHITA, KANSAS.

DRAWING-DESK.

1,259,436.

Specification of Letters Patent. Patented Mar. 12, 1918.

Application filed May 5, 1915. Serial No. 25,926.

To all whom it may concern:

Be it known that I, JOSEPH F. PARKS, a citizen of the United States, residing at Wichita, in the county of Sedgwick and State 5 of Kansas, have invented certain new and useful Improvements in Drawing-Desks, of which the following is a specification.

This invention relates to improvements in furniture, and more specifically to drawing desks.

The object of my invention is to provide a drawing desk especially adaptable for school-room use, in that a plurality of drawers are provided so that each member of 15 the various classes may lock his individual instruments, paper, board, and other drafting material in a drawer to which he alone holds the key. This obviates the constant complaint about lost articles in classes of 20 this kind.

A further object of my invention is to provide a desk adaptable for pupils of different heights. This is accomplished by means of a disappearing platform which 25 may be moved out from the base of the desk for pupils short in stature or pushed back into the desk when not required.

A still further object of my invention is to provide an angularly adjustable top 30 adaptable for drawing purposes, together with a drawer for general supplies which may be opened and closed regardless of the position of the top. A locking seat is provided for the bearing upon which the top 35 slides and moves to the angular position, whereby it is rigidly retained in such angular position.

Furthermore, my device is especially desirable for the purpose intended, is comparatively simple in construction and operation, 40 neat in design, and, by reason of its bolted construction, is extremely durable for school-room use.

Referring now to the drawings, which 45 are merely illustrative of my invention,

Figure 1 is a perspective view of my desk closed.

Fig. 2 is a perspective view of my desk in operative position.

Fig. 3 is detail sectional view illustrating the assembling of the top upon the body portion.

Fig. 4 is a detail perspective view of the hinged end of the side rail and the automatic lock.

Referring further to the drawings, where-

in similar reference characters designate similar parts throughout the respective views, 1 designates the exterior frame of my drawing desk having panels 2 set in the 60 sides and rear thereof. The front is partitioned into drawer sections by means of division strips 3, the uppermost and lowermost of said strips being somewhat wider than the other of said strips, and serving 65 as rails interposed between the sides of said frame 1. Each of the drawers 4, excepting the top drawer 5, is slidably mounted within its section by means of slides 6, adapted to engage with grooves 7 formed upon both 70 sides of said drawers 4. The bottom drawer is covered by a flooring 9 even with the top edge thereof, whereby said drawer is adapted to serve as a raised platform when the drawer is opened. The others of said draw- 75 ers 4 are formed with sides having an angular recess 8 upon the upper edge adjacent the inner face thereof, and extending along the length of said sides. A notch 8^a is formed in the upper edge upon both sides 80 of the drawers 4, excepting the bottom drawer. The oppositely disposed recesses 8 are adapted to form a seat for a drawing board 10, whereby storage for the board is not only provided, but said board serves as 85 a cover for the contents within the drawer. The notches 8^a provide finger holds whereby the board may be grasped and lifted from its seat.

The top rails 11 are curved at 12 upon the 90 forward ends thereof. Horizontal grooves 13 are formed upon the inner faces of said top rails, said grooves terminating at the forward ends thereof in a recessed portion 14 with respect to the plane of said groove 95 13, the forward end and recessed portion of said groove being reinforced by means of a metallic plate 15 secured upon the inner face of said top rails.

The top 16 of the desk is adjustably mounted upon the top rails 11 by means of curved brackets 17, pivotally mounted at one end thereof upon the underside of said top, and formed with an elongated slot 18 there-through. Said brackets are slidably mounted upon threaded bolts 19 which extend outwardly from the sides of said frame 1, and a winged nut 20 is adapted to engage with said bolt and said bracket, whereby said top may be supported at an angle desired. 110 Dovetailed cleats 21 are mounted upon the under side of said top so as to run parallel

to the top rails 11 and be adjacent thereto when said top rests flat upon said rails. Said cleats 21 have slides 22 secured upon the inner faces thereof and pins 23 upon the outer faces thereof. Said slides are adapted to engage with grooves 24 formed in the sides of the top drawer 5, said top drawer being substantially half the depth of the other drawers, thereby leaving a well (not shown) in the rear thereof wherein models may be stored. Said pins are adapted to slide within the grooves 13 as the top is moved forwardly and to seat within the grooved recesses 14 when the top is adjusted to the angular operative position, thereby preventing the movement of the top backwardly except by first raising the forward end thereof and releasing the winged nuts from engagement with the brackets.

The utility, adaptability, and advantages of my improved form of drawing desk being obvious, it is unnecessary to further enlarge upon the same herein.

Having now described and pointed out the new and useful features of my invention, I do not limit myself to the shape of certain parts where the shape is not essential, nor do I restrict myself to the exact details of

construction shown and described, but mean and intend to claim all equivalents and variations thereof not departing in principle from my invention and falling within the purview of the appended claim.

What I claim as my invention and desire to secure by Letters Patent is:

A device of the class described including a frame having a plurality of drawers slidably mounted therein, top rails on the frame having rounded forward extremities, said rails having longitudinally extending slots on their inner faces terminating at their front ends in downwardly extending enlarged portions, a top for said frame, cleats mounted on the under surface of said top and disposed adjacent the top rails, pins mounted on said cleats and adapted to be positioned through the slots in said rails, and means for locking said top in various adjusted positions when the said top is moved forwardly until the pins pivotally engage the enlarged portions of said slots to permit a swinging movement.

In testimony whereof I affix my signature hereto.

JOSEPH F. PARKS.
